MARRACCAS RATTLING DEVICE

George Ashley Boykins, Bronx, N. Y.

Application July 22, 1946, Serial No. 685,298

1 Claim. (Cl. 84—422)

1

This invention relates to musical instruments and more particularly to a marracas rattling device.

It is an object of this invention to provide a marracas rattling device whereby the marracas may be rattled by the foot of a drummer.

Another object of this invention is to provide a rattling device which may be rhythmically operated by the foot of a drummer whereby his hands may be left free to use the drumsticks or to use other instruments or devices associated with a drummer's paraphernalia.

Another object of this invention is to provide a marracas rattling device which is extremely simple in construction and operation, thereby precluding the possibility of mechanical failures and providing a highly efficient device which may be manufactured and sold at a reasonable cost.

With the above and other objects in view, my invention consists in the arrangement, combination and details of construction disclosed by the drawings and specification, and then more particularly pointed out in the appended claim.

In the drawings,

Figure 1 is a side elevation, partly broken away, of the marracas rattling device,

Figure 2 is a front elevation, partly broken away,

Figure 3 is a section taken on the line 3—3 of Figure 2,

Figure 4 is a sectional view, partly broken away, through the device and its attaching means.

Referring to the drawings, the numeral 10 designates generally a rattling device constructed according to an embodiment of my invention. This device is intended to be used primarily by drummers so that this instrument may be actuated by the drummer's foot in time with the music in much the same manner as a bass drum beater, so that the drummer's hands may be free to use other instruments or devices at the same time, as it frequently happens that the drummer's score requires the use of certain instruments simultaneously. Heretofore, on such occasions, another member of the orchestra has been called upon to assist the drummer, and this device will enable the drummer to use these instruments and not require the use of an assisting member for certain renditions.

The marracas rattling device comprises an elongated flat base 11 or floorboard for substantially supporting the device 10. An L-shaped supporting arm 12 is fixed to one end of the base 11 by bolts 14 or other suitable attaching

2

means and extends upwardly from the base 11. The arm 12 is formed with a bifurcated upper end providing a pair of upwardly extending arms 15 having aligned transverse bearings 16 at their upper ends. A bolt or axle 17 is carried loosely in the bearings 16 and extends outwardly from the outer side of one of the bearings 16. The axle 17 is adapted to be rotated in the bearings 16 and a crank 18 is provided on the bolt 17 to which a series of levers is attached for rocking the bolt 17 in the bearings 16. The crank 18 comprises a disc 19 fixed on the shaft 17 between the bearing 16 and arms 15, and a lever or arm 20 secured to the disc 19 and extending radially therefrom. The arm 20 may be fixed to the disc 19, or by engaging in a radial slot 21 in the disc 19, or by other suitable attaching means.

A connecting link or lever 22 is pivotally connected at one end to the outer end of the lever 20 and is adapted to extend downwardly therefrom. The link 22 is attached to one end of a pedal 24, the other end of which is hingedly connected to the rear end of the base 11 by a hinge 25. A hook 26, fixed on the front end of the pedal 24, engages in an opening in the lower end of the link 22. The link 22 may be made of a flat strip of metal twisted ninety degrees intermediate its length as shown at 27 in Figure 1. A coil 28 is fixed between the pedal 24 and base 11 adjacent the hinge 25 and constantly urges the pedal 24 upwardly to a raised position and the crank 18 to an upwardly inclined position from the shaft 17.

Fixed on the shaft 17 outwardly of the bearings 16 and arms 17 there is a disc 29 for supporting a pair of marracas 30.

A pair of oppositely extending outwardly inclined supporting arms 31 are fixed to the disc 29 by bolts 32 and extend radially therefrom. The marracas 30 are each secured in a cup 34 by glueing or other suitable attaching means, and the cup 34 is provided with a rearwardly extending rod 35 which is attached to the arms 31 by U-bolts 36 which engage about the rod 35 and through the arm 31.

In the use of this marracas rattling device 10, as the pedal 24 is depressed, the link 22 rocks the shaft 17 in the bearing 16 and the disc 29 to which the marracas 30 are attached. The marracas 30 are rattled in their rotation and as the pedal 24 is fully depressed, the crank 18 has not reached a dead center position relative to the link 22 so when the pedal is permitted to be raised again by the spring 28 and the marracas rattled again on their rotation back to the starting position.

I do not mean to confine myself to the exact details of construction herein disclosed but claim all variations falling within the purview of the appended claim.

What I claim is:

A marracca's rattling device comprising a base, a spring-pressed pedal rockably carried by said base, an upright standard fixed to said base and having a bifurcated upper end, a pair of spaced bearings carried by said upper end, a shaft journaled through said bearings, crank means fixed to said shaft between said bearings, a link connected between said pedal and said crank means, a plate fixed to one end of said shaft, a pair of oppositely disposed angular elongated bars fixed 15

to and extending radially from said plate, a cup shaped member having a shank thereon removably secured to each of said elongated bars, and a marracca secured in each of said cup shaped members.

5 GEORGE ASHLEY BOYKINS.
